CLAIM

The ornamental design for a video switcher, as shown and described.

DESCRIPTION

FIG. 1 is a front left side isometric view of a video switcher in accordance with the new design;

FIG. 2 is a front elevational view thereof;

FIG. 3 is a left side elevational view thereof, a right side elevational view being a mirror image thereof;

FIG. 4 is a rear elevational view thereof;

FIG. 5 is a top plan view thereof; and,

FIG. 6 is a bottom plan view thereof.

The broken lines shown in FIGS. 1, 2, 4 and 6 show unclaimed environmental subject matter and form no part of the claimed design.
